FOLDING CHAIR

Nicolás Hermilio Celestino Sciarrillo, Cayetano
 Enrique Nicolás Sciarrillo, and Reinaldo Her-
 milio Sciarrillo, Buenos Aires, Argentina

Application April 25, 1951, Serial No. 222,796

1 Claim. (Cl. 155—147)

1

The invention relates to a folding chair which is highly simple both for use as well as manufacture.

An object of the invention is to provide a chair which will offer a soft seating means;

Another object of the invention resides in constructing a chair provided with a back which can be adjusted to the body of the person using the chair;

Still another object of the invention resides in constructing a chair with the smallest possible quantity of material; making it thus very light; enabling it to be manufactured rapidly and simply; reducing thus the cost of manufacture; avoiding complication and inconvenience during folding and unfolding; giving to the chair a new, attractive appearance and finally disposing the elements thereof in such a way that the folded chair may be reduced to a minimum of volume.

For better comprehension of the invention and in order to enable one to readily practice the same, a drawing of an illustrative embodiment is added wherein:

Fig. 1 is a perspective view of a chair embodying the present invention and seen laterally from behind in position of use;

Fig. 2 is a side elevational view, also in position of use;

Fig. 3 is a front elevational view of the chair in folded position, reduced to the smallest volume thereof.

In the various figures of the drawing the same reference numbers indicate the same or corresponding parts.

In conformity with the purpose stated above, for manufacturing each chair it will be sufficient to use only six prismatic laths of rectangular cross-section, five cylindrical sticks for connecting the six laths, and providing the frame formed by the cylindrical sticks and laths at suitable sites with three canvas sheets of quadrilateral shape. Nothing else.

The six laths are used in three pairs. A first pair $1a$ and $1b$ form the two fore jamb posts 1 which are each provided with a central hole 2 and with a second hole 3 near one end thereof. The second pair $4a$ and $4b$ form the two hind jamb posts 4 which are each provided with a first hole at the same height as hole 2 of each fore jamb post 1 , and with a second hole 5 again at the same height as hole 3 of jamb post 1 , and finally with a third hole 6 near the end of said hind jamb post 4 which is adjacent to the previously mentioned hole 5 . The third pair of laths $7a$ and $7b$ are each provided with a hole 8 near

one end of each lath and a second hole separated from the hole 8 by the distance between the holes 5 and 6 and arranged to coincide with hole 5 when the parts are assembled in the manner hereinafter described.

The connection of these three pairs of jamb posts 1 , 4 and 7 is effected by means of five cylindrical sticks which all have a uniform diameter which is greater than holes 2 , 3 , 5 , 6 and 8 . At each end of each stick a portion reduced in diameter is formed so as to enable fitting it into the corresponding hole. Thus stick 9 forms the connecting means between jamb posts $1a$ and $4a$ of one side and the corresponding jamb posts $1b$ and $4b$ of the opposed side. The ends of stick 9 are not glued so as to enable jamb posts 1 and 4 to effect a rotatory movement round each fitted end of stick 9 . Another stick 10 will form the connecting means between the perforated ends of the two fore jamb posts $1a$ and $1b$. As this stick 10 will remain seated fixedly within holes 3 , it may be glued to the parts $1a$ and $1b$ so as to give to the construction greater rigidity during use. A third stick 11 forms a connecting means between the perforated ends of the two hind jamb posts $4a$ and $4b$ and as also this stick 11 will remain fixedly within holes 6 , it also may be glued so as to strengthen the construction against wear and tear. A fourth stick 12 forms a second union between the two hind jamb posts $4a$ and $4b$ at a location below stick 11 and it will unite at the same time the two upper jamb posts $7a$ and $7b$ by extending through the holes which have been made for this purpose in jamb posts $4a$ and $4b$ as well as in jamb posts $1a$ and $1b$. Stick 12 may be glued into jamb posts $4a$ and $4b$, but not into jamb posts $7a$ and $7b$ which are arranged on the outside, thus enabling jamb posts $7a$ and $7b$ to effect a rotatory movement round the tenon of said stick 12 . Finally a fifth stick 13 will form the connecting means between the perforated extremes of the two upper jamb posts $7a$ and $7b$. This stick 13 again may be glued, as it will remain seated fixedly within holes 8 .

The chair is completed by the addition of three canvas sheets to the frame described above. One sheet 14 will be stretched or spanned adequately, for example by doubling the extreme of the sheet round the corresponding stick and sewing it together so as to retain it around the latter, between stick 10 and stick 12 , thereby forming the seat of the chair. A second canvas sheet 15 will be stretched in the same fashion between the two non-perforated extremes of the upper jamb posts

7a and *7b*, thereby serving as a back rest to sustain or support the body of the person seated upon the chair. A third canvas sheet *16* extends between sticks *11* and *13*, and is secured to the two sticks *11* and *13* in the same way as the canvas sheet *14* is secured to the sticks *10* and *12*. This third canvas sheet *16* will strengthen or support the back part of the chair, particularly when the user of the chair inclines the back part of the chair toward the rear, as indicated by arrow *17* in Figures 1 and 2, placing the chair thus in a position of comfortable repose for the user.

During use, the folding chair which forms the subject-matter of this invention will occupy the unfolded position shown in Figures 1 and 2, or even a position wherein the pair of upper jamb posts *7a* and *7b* is still more inclined towards the rear if it is wished to repose comfortably upon the chair, but when the chair is not in use, it is possible to fold it into a minimum volume and keeping it thus folded at any suitable place of storage. For folding the chair, it is only necessary to push stick *10* towards stick *12* so as to bring jamb posts *4* upon jamb posts *1*. For reducing the length of the folded chair, the upper jamb posts *7* may be turned in the direction of arrow *18* around the tenons seated within hole *5* so that the parts of jamb posts *7a* and *7b* which carry canvas sheet *15* will move around *5* and will then occupy the inverted position seen in Figure 3, thus reducing the chair to a really small volume.

The new chair is particularly suited for mass manufacture as it is composed of very few elements which are similar to each other. In this sense, attention may be called to the ease with which the perforation of the holes can be effected jointly. The total number of holes to be made is fourteen, but these fourteen holes can be made in only three operations, as simultaneously in a first operation hole *2* can be perforated in four jamb posts by placing the four jamb posts *1a* and *1b*, *4a* and *4b* one over the other; in a second operation by placing all six jamb posts one over the hole *3* can be perforated simultaneously with hole *5*; and during a third operation by placing the four jamb posts *4a* and *4b* and *7a* and *7b* one over the other with the holes *5* in registration; holes *6* and *8* can be perforated, thereby substantially reducing the cost of manufacture.

We claim:

A folding chair comprising a first pair of parallel lath members, a first cross-member extending between said first pair of lath members at one end of the latter, a second cross-member extending between said first pair of lath members intermediate the ends of the latter, a second pair of parallel lath members pivotally mounted intermediate their ends on said second cross-member for scissoring movement relative to said first pair of lath members, a third cross-member extending between said second pair of lath members at one end of the latter, a fourth cross-member parallel to said third cross-member and extending between said second pair of lath members at locations adjacent to and spaced from said one end of the latter, a third pair of parallel lath members each pivotally mounted at a location adjacent to and spaced from one end thereof on said fourth cross-member, a fifth cross-member extending between said one end of said third pair of lath members, a first flexible sheet attached at its opposite end portions to said first and fourth cross-members to provide a seat, a second flexible sheet attached at its opposite ends to the other end portions of said third pair of lath members to provide a back rest, and a third flexible sheet attached at its opposite end portions to said third and fifth cross-members for limiting the swinging movement of the back rest.
